J. SPECKHARDT

ROWBOAT

Filed Sept. 10. 1924

INVENTOR
J. Speckhardt

BY
F. Ledermann
ATTORNEY

UNITED STATES PATENT OFFICE.

JOHN SPECKHARDT, OF JERSEY CITY, NEW JERSEY.

ROWBOAT.

Application filed September 10, 1924. Serial No. 736,812.

To all whom it may concern:

Be it known that I, JOHN SPECKHARDT, a citizen of Germany, residing at Jersey City, in the county of Hudson and State of New Jersey, have invented certain new and useful Improvements in Rowboats, of which the following is a specification.

The main object of this invention is to provide a rowing device whereby the person using the same may be conveniently seated and rowing carried on with the least amount of exertion. The usual type of rowing device consists of a pair of oar-locks in which the oars are mounted and the operator usually faces rearward to propel the boat forwardly. This facing rearward of the operator is necessary owing to the fact that the greatest strength of the arms may be exerted when pulling on the oars and during this pulling, the oars are dipped in the sea and the boat forges ahead during this time, after which the oars are again pulled forwardly by the operator to start the next stroke. Unusual dexterity and coordination of strength is required to operate the boat in the reverse manner, that is, by facing forward and pushing at each active stroke on the oars. With this device, however, the operator faces forward in the boat and pulls on the oars to accomplish the active stroke.

Another object is to provide a rowing device having means thereon which anchors the oars to the device and permits a quick disengagement so that the oars may be stored in a safe.

These and other objects will become apparent in the description below, in which characters of reference refer to like-named parts in the drawing.

Referring briefly to the drawing, Figure 1 is a top plan view of a dory showing the rowing device mounted thereon, said device being commonly used in pairs.

Figure 2 is a top plan view of the rowing device with the oars removed therefrom and a section of the casing broken away to disclose its contents.

Figure 3 is an elevational view of Figure 2, one half of which is shown in section to illustrate the means by which the oars are attached to the device.

Referring in detail to the drawing, the numeral 10 indicates the gunwales of a dory, the same being curved to form a stream line boat in which the bow seat 11 and a stern

seat 12 are built. On the upper edge of the gunwales intermediate the length of the same and preferably at the center of the boat, freight brackets 13 are rigidly mounted from which a pair of ears 14 extend upwardly. These ears are provided with openings in which a pin 15 is securely mounted, the pin having holes at both ends thru which cotter pins are inserted to retain the pin in place in the ears. An ear 16 integral with the base plate 17 is mounted on said pin 15 between the ears 14 and anchors the rowing device to the gunwale of the ship. A pair of spaced-apart openings 18 are provided in the base plate 17 for the purpose of receiving the reduced ends of pivot studs 19, said studs extending upwardly from the top surface 20^a of the plate 17. On these studs 19, sector gears 20 and 21 are rotatably mounted. The teeth 22 are formed on the mutually adjacent peripheries of these sectors and engage each other. From the sector 21, an arm 23 extends radially outward and is adapted to have the handle bar 24 secured thereto. The opposite sector 20 has a similar bar 25 extending radially therefrom to which the oar 26 is attached. The faces of both sector gears are covered by a flat casing 27 having side walls 28 which encloses said sectors so that the teeth 22 are guarded to prevent anything from coming in contact with them. This casing is retained in place over the sectors by the hands 29 of the studs 19.

The ears 26 and handle bars 24 are retained in place on members 23 and 25 in a novel manner. The means comprises bolts 30 which pass thru openings 31 in members 23 and 25 and the heads 32 of said bolts are supported on the arms 23 and 25. These bolts extend from the lower surfaces of the arms and pass partly thru the length of the openings 33 provided in the oars 26 and handle bars 24. From the lower ends of these bolts curved tongue elements 34 extend and have heads 35 on their lower ends, the shoulders of said heads engaging the surfaces of the oars and handle bars and thus retain the latter rigidly connected to the arms 23 and 25. All of the bolts 30 are provided with axial channels 36 into which a pin 37 may be inserted.

In propelling a boat with this device, the operator sits on the seat 38 and faces forwardly toward the bow 11. The handle bars 24 are then grasped and either alter-

nately or synchronously pushed and pulled. When the handle bars 24 are being pulled, the same are being rotated toward the rear of the boat. This rotates the sectors 21 to 5 the rear also. The handle bars 24 are rotated in one direction and as the teeth 22 of the sectors 21 engage the teeth of the sectors 20, the latter will also be rotated so that the arms 31 to which the oars 26 are attached 10 will be rotated toward the stern of the boat. When these oars 26 are swinging from forward to rear of the boat, the entire device is permitted to be rotated about the pin 15 so that the oars 26 dip into the sea. When the 15 stroke of the oars 26 rearward has been completed, the device is again tilted on the pin 15 to permit the oars to be swung out of the sea and during the same interval, the handle bars 24 are pushed forwardly, causing 20 the oars 26 to rotate forwardly preparatory to dipping the same and starting another stroke.

I claim:—

1. A rowing device comprising a base 25 plate having an ear thereon, a plate bracket adapted to be rigidly mounted on a boat, ears extending from said bracket, a stud passing thru said ears on the bracket and the ears of the base plate to tiltably support 30 the latter, spaced-apart studs on the base plate, sectors mounted on said studs, teeth formed on the peripheries of the mutually adjacent edges of said sectors, the teeth of said sectors being interengaged, an arm extending on each sector, a casing covering 35 said sectors, an oar secured to one arm and a handle bar secured to the opposite arm, said arms having holes therein, hollow bolts passing thru said holes and projecting into 40 openings in the handle bar and oar, a curved resilient tongue having a head thereon at the lower end of each of the bolts, said head being adapted to engage the surface of the handle bar or oar to retain the latter in 45 place, a pin adapted to be inserted into said bolt and engage the curved tongue to release the head of said tongue from engagement with the oar or handle bar.

2. A rowing device comprising a base

plate, a plate bracket adapted to be rigidly 50 mounted on a boat, means connecting said base plate and plate bracket, studs on said base plate, sectors centered on said studs, teeth formed on the peripheries of the mutually adjacent edges of said sectors, said 55 sectors being interengaged, an arm on each sector, a casing covering said sectors, an oar secured to one arm, and a handle bar secured to the arm of the opposite sector, said arms and oar members having aligned openings 60 therein, hollow bolts passing thru said holes and partly thru the length of the holes in the oar members, a curved resilient tongue integral with the bolt members and extending downwardly from the bottom of 65 said bolts, and heads at the ends of said tongues being adapted to engage the oar members and retain the latter locked to the sector arms.

3. A rowing device comprising a base 70 plate, a plate bracket adapted to be rigidly mounted on a boat, means connecting said base plate and plate bracket, studs on said base plate, sectors centered on said studs, teeth formed on the peripheries of the mutually adjacent edges of said sectors, said 75 sectors being interengaged, an arm on each sector, a casing covering said sectors, an oar secured to one arm, and a handle bar secured to the arm of the opposite sector, said arms and oar members having aligned openings 80 therein, hollow bolts passing thru said holes and partly thru the length of the holes in the oar members, a curved resilient tongue integral with the bolt members and extending 85 downwardly from the bottom of said bolts, said tongue extending from the bolt adjacent the bore of said bolt, the curved portion of said tongue being adapted to extend in a curved path diametrically across the bolt, heads at the ends of said tongues, and a pin adapted to be received in the bore 90 of the bolt, said pin being adapted to engage the tongue and shift the latter to disengage the head from the oar member.

In testimony whereof I affix my signature.

JOHN SPECKHARDT.
